(57) **CLAIM**

The ornamental design for a quick access ladder, as shown and described.

DESCRIPTION

FIG. 1 is a perspective view of the quick access ladder showing our new design;

FIG. 2 is a top plan view thereof;

FIG. 3 is bottom plan view thereof;

FIG. 4 is a left side elevation view thereof, the right side being a mirror image;

FIG. 5 is a front elevation view thereof;

FIG. 6 is a rear elevation view thereof;

FIG. 7 is another perspective view of the quick access ladder of FIG. 1 shown in a stowed configuration;

FIG. 8 is a top plan view thereof;

FIG. 9 is bottom plan view thereof;

FIG. 10 is a left side elevation view thereof, the right side being a mirror image;

FIG. 11 is a front elevation view thereof; and,

FIG. 12 is a rear elevation view thereof.

In the Figures the broken lines are for the purpose of illustrating environment and form no part of the claimed design. The quick access ladder is shown with symbolic breaks in its length. The appearance of any portion of the article between the break lines form no part of the claimed design.
